W. W. Williamson Atty.

UNITED STATES PATENT OFFICE.

CHARLES ZERGA, OF PHILADELPHIA, PENNSYLVANIA, ASSIGNOR OF ONE-HALF TO
WILLIAM A. ARMSTRONG, OF PHILADELPHIA, PENNSYLVANIA.

ARCH SUPPORT FOR SHOES.

Application filed August 3, 1921. Serial No. 489,433.

To all whom it may concern:

Be it known that I, CHARLES ZERGA, a citizen of the United States, residing at Philadelphia, in the county of Philadelphia and State of Pennsylvania, have invented new and useful Improvements in an Arch Support for Shoes, of which the following is a specification.

My invention relates to new and useful improvements in an arch support for shoes, and has for its object to provide an exceedingly simple and effective device of this character that will give a resilient support to the arch of a wearer's foot.

Another object of the invention is to provide such a device to be secured in the shoe during the course of manufacture so as to be an integral part of the shoe.

Another object of the invention is to construct an arch support for footwear consisting of a pad of felt, canvas, leather, goring or other suitable material and a flexible non-metallic supporting element such as celluloid, the latter having a coating of plaster Paris, if desired, to render it incombustible under ordinary conditions, the said supporting element also being covered with a suitable textile fabric.

A further object of the invention is to produce a flexible arch support that for all practical purposes will be unbreakable and to affix the same within an article of footwear in the region of the instep, said support being free except along its lower edge.

With these ends in view, this invention consists in the details of construction and combination of elements hereinafter set forth and then specifically designated by the claim.

In order that those skilled in the art to which this invention appertains may understand how to make and use the same, I will describe its construction in detail, referring by numerals to the accompanying drawings forming a part of this application, in which:

Fig. 1, is a perspective view of a shoe showing my improved arch support therein.

Fig. 2, is an enlarged plan view of an insole showing the application of the arch support thereto.

Fig. 3, is an end view thereof.

Fig. 4, is a transverse sectional view through a shoe in the region of the arch sup-

port and illustrating the same located inside the shoe lining.

Fig. 5, is a face view of the support laid out flat; and

Fig. 6, is a sectional view thereof.

In carrying out my invention as here embodied, 2 represents a shoe or article of footwear which may be made of any suitable material and any desirable shape or style and includes an insole 3 to which is attached the lower edge of my improved arch support 4 by suitable attaching means such as stitches of thread indicated by the numeral 5. The support is affixed to the insole in the region of the instep portion thereof or so located thereon that when the insole is in place the support will lie in the instep of the shoe beyond the counter and said support is not attached to any other part of the shoe.

When in place the arch support may be outside of the shoe lining 6 as shown in Fig. 75 1 or it may be located between said lining and the side of the shoe so as to be covered by said lining as illustrated in Fig. 4.

The arch support 4 consists of a pad 7 of felt, canvas, leather, goring or other suitable material, a flexible non-metallic supporting element 8, preferably a sheet of celluloid and a cover 9 of suitable textile fabric to enclose the sheet of celluloid. All of these parts are affixed to each other by suitable means such as for instance cement or stitching and if found desirable the celluloid may be coated on one or both sides with a thin layer of plaster Paris 10 in order to reduce to a minimum the combustibility 90 of the celluloid under ordinary conditions of use.

During the course of manufacture of the arch support and its placement in the article of footwear the celluloid supporting element must be in a soft or pliable state so that it will readily assume the shape of the instep portion of the article of footwear. The sheet of celluloid is softened by the application of any of the well known solvents 100 for this purpose and while in this soft condition it is attached to the other elements of the support and the latter secured to the insole, then the insole with the attached support is placed in position by the ordinary lasting operation which will cause the arch support to conform to the shape of the instep portion of the shoe. When the sol-

vents have evaporated or the celluloid has dried out the last may be removed and the arch support will retain its shape.

The supporting element being of celluloid

- 5 the same is practically unbreakable and being flexible and resilent the arch support will yield to the pressure of the wearer's foot while maintaining a slight pressure upon the arch of the foot and as the foot is raised
- 10 the support will follow the relaxed position of the foot.

An arch support made as herein specified will not be affected by the heat of the body or by weather and climatic conditions.

- 15 One of the particular advantages obtained by this invention is that different thickness of celluloid may be utilized for the supporting element thus regulating the degree of flexibility of the arch support according to whether used with children's or
- 20 adults' shoes or according to the weight of the wearer or according to the pressure desired upon the wearer's foot.

Of course I do not wish to be limited to

the exact details of construction as herein shown as these may be varied within the limits of the appended claim without departing from the spirit of my invention.

Having thus fully described my invention, what I claim as new and useful is:—

In a device of the character stated, an article of footwear having an insole, an arch support comprising a pad to engage the foot of the wearer, a celluloid supporting member affixed to said pad and shaped to correspond to the contour of the article of footwear in the region of the instep thereof, and a covering disposed across said supporting element and affixed to said element and said pad, said arch support being secured along its lower edge to the instep edge of the insole, the remainder of said support being free to follow the movements of the wearer's foot.

In testimony whereof, I have hereunto affixed my signature.

CHARLES ZERGA.
